UNITED STATES PATENT OFFICE.

HENRY M. KELLY, OF OTTAWA, ILLINOIS.

WAGON ATTACHMENT.

SPECIFICATION forming part of Letters Patent No. 645,473, dated March 13, 1900.

Application filed October 20, 1899. Serial No. 734,233. (No model.)

To all whom it may concern:

Be it known that I, HENRY M. KELLY, a citizen of the United States, residing at Ottawa, in the county of La Salle and State of Illinois, have invented new and useful Improvements in Wagon Attachments, of which the following is a specification.

My invention relates to wagons and wagon attachments, and contemplates the provision 10 of a wagon attachment designed to be used in conjunction with a carrier and track with a view of facilitating the removal of corn or other substance from a wagon to a crib or other point of discharge.

15 The invention will be fully understood from the following description and claims when taken in conjunction with the annexed drawings, in which—

Figure 1 is a view, partly in section and 20 partly in elevation, illustrating a wagon equipped with my improved attachment, together with a track and carrier and a corn-crib, one of the boxes of the attachment being shown as elevated to and connected to the 25 carrier. Fig. 2 is a transverse section of one of the boxes of the attachment. Fig. 3 is an inverted plan view of the same.

Referring by letter to the said drawings, 30 A is a track; B, a carrier; C, a fall, and D a cable, which is connected to the carrier, and after taking around sheaves on the fall and carrier and fixed sheaves E F is designed to be connected to a draft-animal.

The track, carrier, and fall are constructed 35 in accordance with the invention of one J. F. Porter and form the subject-matter of his Letters Patent No. 482,412, dated September 13, 1892. The track has a stop a arranged at about the point shown, and the carrier in ad- 40 dition to the usual traveling wheels b and sheaves c is equipped with a catch d, a pivoted hook e, and a vertically-disposed pas- sage f. These parts are so constructed that when the fall C is raised into the passage or 45 socket f of the carrier it will be automatically engaged by the pivoted hook e and by moving said hook will release the catch d and permit the same to fall out of engagement with the stop a. From this it follows that 50 with the fall in its lowered position the carrier is locked against movement on the track;

but when the fall is raised to the carrier the carrier is released and may then be drawn along the track. The catch d of the carrier is also provided with a depending line g. 55 This line is provided in order to enable an attendant, when the carrier has been moved back on the track, to place the catch d in engagement with the stop a and by so doing release the fall C from the carrier and permit 60 said fall to descend.

As shown in Fig. 1 of the drawings, the track A is fixed with reference to a grain-crib G, having an opening h and a receiving-trough i. It may, however, be arranged with- 65 in a grain crib or house, over a runway therein, or at any other suitable point, if desired.

H is a wagon, which is provided with bol- 70 sters j and may otherwise be of the ordinary construction, and I is my improved attach- ment.

The attachment I comprises an open frame J, preferably of rectangular form, which is designed to be placed and secured, if necessary, on the bolsters of the wagon after the 75 manner shown in Fig. 1, and boxes K, also by preference of rectangular form, which are designed to be placed on and held by the frame J against lateral displacement.

The boxes J are similar in construction, and 80 therefore a description of the one shown in detail in Figs. 2 and 3 will suffice to impart an understanding of both. The said box is preferably made of wood and comprises side walls k and a hinged bottom l. It is provided 85 on its upper edge at its several corners with eyes m, which are designed for the engage- ment of hooks n on chains p, which run to a central hook q, designed to be connected to the fall C, before described.

The hinged bottom l of the box K is pro- 90 vided at its free edge with a projection r and is designed to be held in its closed position by a catch s. The catch may be of any suit- able construction, that shown being ful- 95 crumed on one of the walls k of the box and being connected to a cable t, which runs through a guide u on the box and thence downwardly, so as to enable a person stand- ing on the ground to disengage the catch from 100 the projection r, and thereby release the bot- tom l.

At the under side of its bottom *l* the box *J* is provided with cleats or projections *v*. These cleats or projections are designed to rest within the open frame *J* when the box is placed thereon, and thereby hold the said box against lateral displacement. When the two boxes are placed on frame *J*, they serve to hold each other against longitudinal movement in one direction, while the transverse cleats *v*, in conjunction with the end bars of the frame, serve to hold them against longitudinal movement in the opposite direction. In addition to serving as stops to prevent lateral displacement of the boxes when the same are mounted on the frame *J* the cleats *v* materially strengthen the bottoms of the said boxes.

In practice the frame *J* of my improved attachment is placed and suitably secured, if necessary, on the bolsters *j* of a wagon, and the two boxes *K* are placed on said frame, with their depending cleats or projections resting within the same.

The boxes *K* are suitably filled with grain or other substance to be moved, and the wagon is hauled to a point below the track *A*, as shown in Fig. 1, after which the fall *C* is lowered, and the hooks *n* on chains *p* are connected to the eyes *m* on one of the boxes *K*. With this done the draft-animal attached to cable *D* is driven forwardly to raise the box toward the carrier *B*, and when the fall *C* enters the socket *f* of the carrier it will be engaged and held by the hook *e*, and at the same time catch *d* will be released and permitted to drop out of engagement with the stop *a*. The carrier is now released, and the continued forward movement of the draft-animal will serve to move it along the track until the box *K* reaches a point above the trough *i* or other point of discharge, when the draft-animal is stopped and the box is discharged of its contents by an attendant drawing on the line *t*, and thereby releasing the bottom of the box. After the box *K* is dumped the carrier is returned to the position shown in Fig. 1, and the line *g* is drawn upon to place the catch *d* in engagement with the stop *a* and release the fall *C* and permit the box *K* to descend into its original position on the frame *J*. Incident to the descent of the box *K* from the carrier or at any other suitable time its bottom *l* is closed and is secured through the medium of the catch *s*. After one box has been discharged of its contents and replaced on the frame *J* in the manner described the operation is repeated with reference to the other box. When both boxes are discharged of their contents and replaced on the frame *J*, the wagon is hauled off to receive another load.

I prefer in practice to use but two boxes in conjunction with a frame *J*, as shown and described. I do not desire, however, to be understood as limiting myself to the use of two boxes with a single frame, as, when desired, one, two, three, or more boxes may be em-

ployed without departing from the scope of my invention.

It will be appreciated from the foregoing that my improvements are simple and inexpensive, and yet are adapted to greatly facilitate the removal of grain or other substance from a wagon to a crib, but two trips of the carrier *B* being necessary to discharge a wagon-load. It will also be observed that the attachment is readily applicable to ordinary wagons, and when desired the frame *J* may be connected to and made a permanent part of a wagon.

It will be obvious from the foregoing that my improvements may be used to advantage on cars and similar carriers, as well as on wagons. I therefore desire it understood that the term "wagon" as herein used is intended to comprehend carriers of all kinds.

I am well aware that it is old to provide a wagon-frame or running-gear with vertically-disposed retaining-apertures to receive vertical dowel-pins on a removable body. I am also aware that a dumping-body for vehicles having a bottom made up of hinged sections is old, and therefore make no claim to the same.

What I claim, and desire to secure by Letters Patent, is—

1. A wagon equipped with an open, rectangular frame, and a removable box arranged on said frame, and having a hinged bottom and a catch for securing the same in its closed position, and also having cleats at the under side of the hinged bottom, arranged within the frame and engaging the inner sides of the bars thereof so as to hold the box against displacement, substantially as specified.

2. A wagon equipped with an open, rectangular frame, and removable, rectangular boxes arranged end to end on said frame, and having hinged bottoms and catches for securing the same in their closed positions, and also having strengthening-cleats at the under side of the bottoms arranged to engage the inner sides of the bars of the frame whereby the boxes are enabled to hold each other against casual movement and displacement, substantially as specified.

3. An attachment for wagons comprising an open, rectangular frame, and removable, rectangular boxes arranged end to end on said frame, and having hinged bottoms, and catches for securing the same in their closed positions, and also having strengthening-cleats at the under side of the hinged bottoms arranged to engage the inner sides of the bars of the frame whereby the boxes are enabled to hold each other against casual movement and displacement, substantially as specified.

In testimony whereof I have hereunto set my hand in presence of two subscribing witnesses.

HENRY M. KELLY.
